(57) **CLAIM**

The ornamental design for hinge a cover, as shown and described.

DESCRIPTION

This application is related to U.S. patent application Ser. No. 12/562,743, titled Coupling Apparatus for Barrier Assemblies and Related Methods and filed Sep. 18, 2009.

FIG. 1 is an isometric view of a hinge cover showing my new design.

FIG. 2 is a top plan view of the hinge cover.

FIG. 3 is a bottom plan view of the hinge cover.

FIG. 4 is a front elevation view of the hinge cover.

FIG. 5 is a back elevation view of the hinge cover.

FIG. 6 is a right side elevation view of the hinge cover; and, FIG. 7 is a left side elevation view of the hinge cover.

The broken lines are for illustrative purposes only and form no part of the claimed design.
